Porter Cleveland, of Albemarle and State of Virginia.

Letters Patent

The schedule referred to in these Letters Patent and making part of the same, containing a description in the words of the said Porter Cleveland himself of his improvement in the Threshing Machine.

To all, to whom these Presents, shall come,
Be it known that I Porter Cleveland in the County of Albemarle,
and State of Virginia have invented a new useful and durable
improvement in Machinery for threshing small grain of every description,
now called Cleveland's rotary roller shaft and half roller shaft
threshing machine for threshing wheat and other small grain from
off the stalk, which machine and its manner of use are as follows:

This machine is constructed by having a frame, three feet long
by two feet nine inches from end to end, made on top, according to the
power required to give it motion. The frame may be made of
any suitable materials, consisting of four posts two feet and a
half long, four and a half inches by three inches, into these posts are
framed with double beams two side girders fourteen inches wide
by three inches thick, and four other girders three and a half inches
by three inches, are framed into said posts which make the ends of
the frame; on the top of these posts are put two caps of timber
three and a half inches by three inches, extending six inches beyond each
end of the frame.

On the said girders of the frame is placed a
cylinder, six feet 3 inches long and 15 inches in diameter constructed
as follows - On a shaft of iron 17/8 inches square of suitable length
for the frame are placed two wooden heads 2 inches thick, turned
round of sufficient diameter to receive staves 3 inches thick, so as to
give the full diameter of 15 inches to the cylinder. In this cylinder are
placed 7/8 or more or less brace and mailed teeth in proportion to
the length which are placed in the cylinder at suitable distance

from each other, either in spiral, half spiral or straight rows, at the option of the builder so as to have 1 or more teeth in a row round the Cylinder. This tooth is made as follows, of wrought iron $\frac{3}{8}$ of an inch square bent in an angular form having one prong straight, which is driven 3 inch¹ into the cylinder leaving it $1\frac{1}{4}$ inch out. The other end or prong forms a curved brace of 6 or more inch long through which are driven into the cylinder two large nails as seen in fig. 6.

The concave bed is made or constructed of cast iron roller shafts 2 feet 3 inch¹ long. The rollers 4 inch in diameter $\frac{3}{8}$ of an inch thick at the outer edge and $\frac{1}{2}$ inch thick where it becomes solid with the shaft; the solid part of the shaft $1\frac{1}{2}$ inch in diameter more or less. The rollers are $2\frac{1}{2}$ inch apart from center to center as in fig. 2.

Circular Segments of cast iron are made 3 inch wide and 1 inch thick of sufficient length with holes 1 inch in diameter so as to receive five more or less roller shafts at a proper distance to roll without touching each other as in fig. 3.

5. roller shafts are first alternately in the circular segments as in fig. 4, and then placed in the frame at proper distance from the cylinder and the segments screwed fast to the side girders.

The rollers may be either smooth on the outer edge or notched at the option of the builder, notches on the edge will give them more motion.

The roller shaft may be lifted out on this concave bed and the half circle or half roller shaft before wanted, used in its stead. The half roller shaft is made in the form of half of the roller shaft as in fig. 5. this is placed in the frame by being screwed to a wooden concave bed which is let into the side girders by means of circular grooves cut in the girders.

What I claim as my invention and improvement is the brace and notched tooth in the Cylinder, the roller shaft, and the half circle or half roller shaft in the concave bed and the manner of frame in which the concave bed is put together so as to be used for the aforesaid purposes.
